UNITED STATES PATENT OFFICE.

EDWIN C. BALLMAN, OF ST. LOUIS, MISSOURI, ASSIGNOR TO VALLEY ELECTRIC COMPANY, OF ST. LOUIS, MISSOURI, A CORPORATION OF DELAWARE.

VARIABLE RESISTANCE.

Application filed February 10, 1923. Serial No. 618,259.

This invention relates to resistance units, and more particularly to adjustable resistance units arranged for convenient mounting on the apparatus with which the resistance is to be used.

One of the objects of this invention is to provide an adjustable resistance unit which may be adjusted so as to vary the resistance gradually and which may be fixed in its adjustment at a desired point.

Another object of this invention is to provide a resistance unit which shall be conveniently arranged for mounting.

Another object of this invention is to provide a unit which shall be compact in design and amply ventilated.

Further objects will appear from the detail description taken in connection with the accompanying drawing, in which:

20 Figure 1 is a view in elevation of a resistance embodying this invention;

Figure 2 is a bottom view of Figure 1; and

Figure 3 is a partial section on line 3—3, 25 Figure 1.

In accordance with this invention the resistance conductor has the form of a wire usually of one of the so-called resistance materials. This wire is coiled upon a supporting tube or barrel 1 of insulating material. The surface of the barrel 1 may be grooved helically so as to provide a bed in which the wire may lie so as not only to prevent its displacement from the support, 30 but to insure a uniform and permanent spacing of the successive turns. The conductor wire 2 is doubled and has the looped end attached to a screw 3 or other fastening device for fixing the end of the wire to the barrel. When the loop has been anchored 35 to the screw 3, the wire is then wound double so as to lie in the helical grooves on the barrel. The barrel is wound full of wire, except for the space occupied by the supporting terminals at the bottom.

40 The barrel 1 is itself mounted upon a pair of metallic supporting terminals 4 and 5 extending in preferably opposite directions from the bottom of the barrel. These terminals are each provided with an up-turned lip or flange 6 bent so as to conform to the outer surface of the barrel and attached thereto by means of screws 7 and 8. These screws may be equipped with nuts and 45 spring-lock-washers as indicated in Figure

2 so as to prevent their working loose. The terminals 4 and 5 provide a pair of outwardly extending wings equipped with notches 9 and 10 for engaging the terminals upon which the resistance unit is to be 60 mounted. These notches are turned in different directions at right angles to each other so that they may be engaged with a pair of terminals having a fixed spacing in a manner well known in the art. 65

The barrel 1 is provided at diametrically opposite points near the bottom with perforations 11, only one of which is shown. These perforations are placed adjacent a pair of opposite screws 8 and the ends of the resistance conductor wire are passed through these perforations to the inside of the barrel when the wire has been completely wound thereon. After passing to the interior of the barrel, the ends are secured under the 70 spring-washers of the screws 8. One end of the resistance conductor wire is thus connected to each of the terminals 4 and 5 so that current may be led into and out of the resistance by means of these terminals. 75

80 Mounted on the barrel 1 and surrounding the same is a circular metallic collar 12, the ends 13 of which are turned up as illustrated in Figure 2 to form lips provided with perforations through which a clamping screw 85 14 may be passed. A nut 15 may be soldered to the collar 12 and the corresponding up-turned lip 13 may be engaged by the screw 14 for clamping the collar on the barrel. The collar 12 is provided at spaced 90 points with indentations 16 adapted to provide inwardly projecting knobs or buttons. The collar 12 is placed upon the barrel in such a way that each of these buttons comes between a pair of adjacent turns of the conductor 95 2. Since the conductor is wound so that the turns project somewhat from the surface of the barrel, the collar will be retained in position by the engagement of these buttons with the wire. At the same time each button forms a metallic bridge between adjacent turns of wire so as to short circuit a pair of turns. It will be evident that by loosening the screw 14 slightly the collar may be turned on the barrel so as to cause a button 16 to slide along between the adjacent wires. Since the wires are in the form of a screw thread, rotation of the collar 12 will gradually feed the same along the barrel in one direction or another ac- 100 105 110

ording to the direction of rotation, the collar being guided by engagement of the buttons 16 with the wires 2. Thus a very gradual adjustment of resistance is obtained, since by moving the short circuiting button 16 along the wire as described, a greater or less extent of wire may be included in the circuit between the terminals 4 and 5. The resistance can thus be gradually adjusted to any desired value within its range and when the desired adjustment has been obtained, the screw 14 may be tightened so as to clamp the collar 12 securely in position.

It will, therefore, be evident that a simple and effective resistance unit is provided by this invention. The barrel 1 may be simply and cheaply constructed of molded insulation or other suitable insulating material. If molded insulation is used the groove can be molded therein simultaneously, thereby cheapening the construction. The doubly wound resistance wire provides a practically non-inductive resistance. The adjustable collar 12 being adjustable by means of the screw thread-action described above provides a very gradual and accurate adjustment of the resistance and the clamping feature provides for permanently setting the resistance at the desired adjustment. The hollow barrel construction provides for easy ventilation of the unit both inside and out.

It is obvious that various changes may be made in details of construction without departing from the spirit of this invention; it is, therefore, to be understood that this invention is not to be limited to the specific details shown and described.

Having thus described the invention, what is claimed is:

1. An electrical resistance unit comprising

a helically grooved barrel, a resistance conductor wound in said groove, a movable contact collar surrounding said barrel and punched to provide a plurality of rounded interior projections spaced one from the other and adapted to contact with adjacent turns of said conductor and be guided thereby.

2. An electrical resistance unit comprising a helically grooved barrel, a resistance conductor wound in said groove, a movable contact collar surrounding said barrel and punched to provide a plurality of rounded interior projections spaced one from the other and adapted to contact with adjacent turns of said conductor and be guided thereby, and means for clamping said collar in adjusted position.

3. An electrical resistance unit comprising a helically grooved barrel, a resistance conductor wound in said groove, a movable contact collar surrounding said barrel and punched to provide a plurality of rounded interior projections spaced one from the other and adapted to contact with adjacent turns of said conductor and be guided thereby, and clamping means for said collar adapted to shorten the circumference thereof.

4. An electrical resistance unit comprising a helically grooved barrel, a resistance conductor wound in said groove and a movable contact collar surrounding said barrel and having spaced rounded interior projections adapted to contact with adjacent turns of said conductor and be guided thereby, and supports for said barrel adapted to provide terminals for said conductor.

In testimony whereof I affix my signature this 28th day of December, 1922.

EDWIN C. BALLMAN.
